UNITED STATES PATENT OFFICE.

LOWRY W. STATLER, OF PIQUA, OHIO.

DUMPING-WAGON.

SPECIFICATION forming part of Letters Patent No. 688,357, dated December 10, 1901.

Application filed September 28, 1901. Serial No. 76,940. (No model.)

To all whom it may concern:

Be it known that I, LOWRY W. STATLER, a citizen of the United States, residing at Piqua, in the county of Miami and State of Ohio, have 5 invented certain new and useful Improvements in Dumping-Wagons; and I do hereby declare the following to be a full, clear, and exact description of the invention, such as will enable others skilled in the art to which 10 it appertains to make and use the same.

The object of this invention is to provide an improved dumping-bed or means for unloading wagons or cars; and the invention consists of a wagon or car having its bed composed chiefly of sections of inverted-V shape 15 in cross-section, with openings between the bases of such sections to be covered by slats of a frame that slides in ways in the sides of the wagon or car.

20 In the accompanying drawings I have shown one embodiment of my invention.

In the drawings, Figure 1 is a vertical longitudinal sectional view. Fig. 2 is a bottom plan view, and Fig. 3 is a vertical transverse 25 sectional view.

In the several views, 1 denotes the inverted-V-shaped sections of the bottom or bed of the wagon. These sections are arranged at such 30 distance apart as to allow the free discharge of the load between the sections. The upper sides of these sections are preferably covered with sheet metal to protect the wood and facilitate the discharge of the load. The ends of the wagon bottom or bed are furnished 35 with inclined sections 2. The openings between the edges of sections 1 and 2 are closed by means of slats 3, that are joined together in one frame by means of strips of metal 3^a. The ends of the slats 3 are supported in 40 grooves or channels formed by bolting, riveting, or otherwise securing a strip of angle-iron 4 along the lower edge of each of the opposite side pieces of the wagon-body. The slat-frame is shown to be operated by means 45 of a lever 5, fulcrumed near one side of the bottom or bed of the wagon and having a handle protruding at the opposite side. This le-

ver is connected with the slat-frame by means of a link 6, and to give strength to the connection the slat-frame has secured to it metallic straps 7, that extend from about the middle of the sides of the frame to the middle of the end thereof. The drawings show the discharge-openings closed. By pulling the free end of the lever toward the end of the 50 wagon the slats are all pulled from under the spaces between the bed-sections, when the contents of the wagon will discharge by gravity through the openings. The inclination of the surfaces of the upper sides of the sections 55 is such that the entire contents of the wagon will be discharged. Any suitable means can be employed to fasten the lever when the openings are closed.

The slat or valve frame can be operated by 60 devices other than that shown in my drawings, and I therefore do not wish to be understood as confining myself to the particular means shown.

What I claim, and desire to secure by Letters Patent, is—

1. In a dumping-wagon, a bed comprising separated parallel sections of inverted-V form in cross-section, and a frame composed of horizontally-arranged parallel slats or valves with 70 means whereby the same can be slid horizontally to open or close the openings between the inverted-V-shaped sections, substantially as described.

2. In a dumping-wagon, a bed comprising 80 separated parallel sections of inverted-V form in cross-section and inclined portions at the ends of the bed, and a frame composed of horizontally-arranged parallel slats or valves with means whereby the same can be slid horizontally 85 to open or close the openings between the inverted-V-shaped and end sections, substantially as described.

3. In a dumping-wagon, a bed composed of inclined discharging-surfaces with discharge- 90 openings between them, a slat or valve frame adapted to open and close said discharge-openings, and angle-irons secured to the lower edges of the sides of the wagon-body forming

with said edges grooves or channels in which said slat or valve frame is supported and slides, substantially as described.

4. In a dumping-wagon, a bed comprising separated parallel sections of inverted-V form in cross-section, and a frame composed of horizontally - arranged parallel slats or valves joined rigidly together and adapted to be slid with a direct movement to open and close the

openings between the aforesaid inverted-V- 16 shaped sections of the bottom, substantially as described.

In testimony whereof I affix my signature in presence of two witnesses.

LOWRY W. STATLER.
